UNITED STATES PATENT OFFICE.

EDGAR H. FREEMAN, OF TRENTON, NEW JERSEY, ASSIGNOR TO E. H. FREEMAN ELECTRIC COMPANY, A CORPORATION OF NEW JERSEY.

CANDELABRUM-SOCKET.

1,245,326.

Specification of Letters Patent. Patented Nov. 6, 1917.

Application filed March 22, 1917. Serial No. 156,680.

To all whom it may concern:

Be it known that I, EDGAR H. FREEMAN, a citizen of the United States, residing at Trenton, in the county of Mercer and State of New Jersey, have invented certain new and useful Improvements in Candelabrum Sockets, of which the following is a specification.

This invention relates to an improvement in that type of electrical lamp sockets employed for candle fixtures, and known as the candelabrum socket or candle socket.

In electrical sockets of the type referred to, considerable difficulty is frequently experienced in removing and replacing the relatively long insulating casing which surrounds and incases the socket shell and the wire terminal, and in some forms of construction it is almost impossible for the workman to remove and replace this part of the fixture when wiring the same without damage or injury thereto. This is particularly true with the well known form of candle socket which has been on the market for a number of years, and which involves the provision of a threaded engagement between the paper or fiber insulating casing and the screw shell contact. This threaded engagement, in the old type of candle socket which is relied upon to secure the casing in place, is generally so close and tight-fitting as to make it very difficult, and sometimes impossible without the use of a tool, to remove the casing so as to uncover the wire terminals after it has once been placed in position.

Also, in some forms of construction the porcelain or other insulating socket body which carries the lamp terminals and the wire terminals has been formed with an integral shoulder against which the insulating casing or tube is seated. However, this is an objectionable feature on account of the casing usually being jammed down so tight against such shoulder as to contribute materially to the fast-binding of said casing and thereby prevent the workman from easily manipulating the same to uncover the wire terminals when necessary.

Accordingly, it is the purpose of the present invention to provide a simple and practical casing lock for candle sockets. This casing lock is a separate device which entirely obviates the necessity of the insulating casing being screwed to or otherwise

carried by the screw shell contact, and also obviates the necessity of forming the insulating socket body with a shoulder or abutment of any kind. Furthermore, it is proposed, by the present invention to provide a casing lock or retaining means permitting the insulating casing to have a loose and free sliding fit over the socket and which may be automatically locked in place by simply telescoping the casing over the socket. Also, the invention provides means whereby the workman can release the casing from its lock by the simple act of slightly rotating it, and then lifting the same from over the insulating socket body.

Other novel features and advantages will be readily apparent to those familiar with the art and it will be understood that the invention is susceptible of structural modification without departing from the principle thereof or sacrificing any of its advantages.

A practical embodiment of the invention is suggested in the accompanying drawings, in which—

Figure 1 is a sectional view of a candle socket embodying the present invention, on a line of section including both lamp terminals and both wire terminals.

Fig. 2 is a similar view on a line of section including the casing locking means.

Fig. 3 is a perspective view partly in full lines and partly in dotted lines showing the several elements comprising the casing lock, and indicating the direction of movement of the casing to effect the locking automatically.

Fig. 4 is a view similar to Fig. 3 showing the casing locked in position, and indicating by dotted lines, the direction of rotative movement to effect a release of the locking element.

Fig. 5 is a detail view in perspective of one of the snap fastening members, and the portion of the insulating casing co-operating therewith.

Similar reference characters designate corresponding parts throughout the several figures of the drawings.

In carrying out the invention no change is required in the standard parts of the ordinary types of candle sockets which have been on the market for a number of years. Accordingly, for purposes of illustration, as shown in the drawings, an ordinary type of candle socket consisting essentially of

the porcelain or equivalent socket base 1 to one side of which is fitted the usual screw shell contact 2 and the center plug contact 3 constituting the lamp terminals, and upon one side of which are arranged the oppositely located wire terminals 4 and 5 respectively in electrical connection with the lamp terminals 2 and 3. The wire terminals 4 and 5 are fitted with the usual binding screws 6, and the entire socket structure is adapted to be incased in the relatively long paper or equivalent insulating casing 7. To complete the socket structure, the insulating socket base 1 has fitted to the outer side thereof the coupling nipple 8 for connecting the socket with the fixture pipe, and said coupling nipple is carried by a holding flange or plate 9 held to the socket base by the retaining screws S.

The present invention relates to the means for locking the insulating casing 7 in place. In this connection, it will first be observed that the socket base 1 is of uniform diameter throughout with no projecting parts or ledges of any character and having its external surface substantially flush with the external surface of the screw shell contact 2. Over these external surfaces the casing 7 fits loosely and freely, and to provide for locking the latter in place, there is employed a separate casing lock. This casing lock preferably consists of a pair of oppositely arranged snap fastening members 10 of duplicate construction and each consisting of an angled plate 11 having an inwardly extending attaching arm 12 and an outer locking arm 13. The attaching arm of each fastening member 10 extends beneath the base 1 and is held in place between the same and the flange 9 by one of the screws S while the locking arm 13 is disposed longitudinally of the socket base 1 in a recess 14 formed in the outer side of said base, and at the junction between the arms 12 and 13 the angled plate is formed with an outstanding abutment lip 15 which constitutes a stop or abutment for the insulating casing against movement in one direction.

The outer locking arm 13 of each fastening member 11 has pressed out from the metal thereof a rounded and beveled catch projection 16. The operation of punching this projection of metal produces a transverse cut-metal holding edge 17 adapted to engage a corresponding holding edge 18 at the bottom of the keeper hole 19 cut into the lower end portion of the insulating casing 7. It will be further observed that the locking arm 13 preferably stands sufficiently free from the base 1 to permit of a spring action so that the fastening member acts as a spring snap fastening which yields when the casing 7 is slid thereover and thereby permits the catch projection 16 to automatically snap into engagement with the hole 19.

The operation of causing the insulating casing 7 to become automatically snapped into locking engagement with the catch projection 16 of the opposite fastening members upon a simple straight longitudinal telescopic movement of said casing will be apparent from Figs. 3 and 5 of the drawings. And, by reference to Fig. 4 of the drawings, it will also be apparent that to release the catches it is simply necessary to give the casing a slight rotative movement with the result of causing the same to slide laterally over the rounded beveled projection 16 and thus automatically depress the same out of engagement with the holes 19, whereupon the casing may be easily slid upward from over the porcelain base 1 and the threaded lamp terminal 3. The beveled formation of the catch projection 16 causes the casing 7 to automatically rise over the said projection when forced downwardly thereover.

From the foregoing, it is thought that the construction, operation and advantages of the herein described improvement will be readily apparent without further description, and it will also be understood that various changes in the form, proportion, and minor details of construction may be resorted to without departing from the spirit of the invention or scope of the appended claims.

I claim:

1. A candelabrum socket including the socket proper carrying a snap-lock spring fastening member and also carrying the lamp terminals and the wire terminals, and an external insulating casing having a free telescopic movement over the entire socket and arranged to cover all of the said terminals and the said spring fastening member, said casing having means automatically interlocking with said spring fastening member.

2. In a candelabrum socket including the socket proper carrying lamp terminals and wire terminals, and a fastening member consisting of a plate having a catch projection, an external insulating casing adapted to engage with said catch projection and arranged to cover both sets of terminals and the said fastening member.

3. A candelabrum socket including the socket proper having an insulating base carrying the lamp terminals and the wire terminals, a fastening member also fitted to the insulating base, and an external insulating casing telescopically fitting over the insulating base and having an automatic engagement with the fastening member upon a straight telescopic movement thereover.

4. In a candle socket, the socket proper, including the base carrying lamp terminals and wire terminals, a fastening member consisting of an angled plate fitted to the base and having a spring locking arm provided

with an outwardly extending catch projection, and an external insulating casing having a keeper opening for automatically engaging the outwardly extending catch projection.

5. In a candle socket, the socket proper, including the base carrying lamp terminals and wire terminals, a fastening member consisting of a plate having an abutment pro-

jection and a catch projection, and an external insulating casing adapted to engage with both projections.

In testimony whereof I hereunto affix my signature in the presence of two witnesses.

EDGAR H. FREEMAN.

Witnesses:

HAROLD PALMER,

WILLIAM P. HAYES.
